UNITED STATES PATENT OFFICE.

ALBERT W. ERDMAN, OF DERBY, CONNECTICUT, ASSIGNOR TO THE DRIGGS-SEABURY GUN AND AMMUNITION COMPANY, OF NEW YORK, N. Y.

ADJUSTABLE STOP FOR CONTROLLING BREECH MECHANISMS OF AUTOMATIC OR SEMI-AUTOMATIC GUNS.

SPECIFICATION forming part of Letters Patent No. 665,198, dated January 1, 1901.

Application filed October 13, 1900. Serial No. 32,974. (No model.)

To all whom it may concern:

Be it known that I, ALBERT W. ERDMAN, a citizen of the United States, residing at Derby, in the county of New Haven and State of Connecticut, have invented certain new and useful Improvements in Adjustable Stops for Controlling the Breech Mechanism of Automatic or Semi-Automatic Guns; and I do hereby declare the following to be a full, clear, and exact description of the invention, such as will enable others skilled in the art to which it appertains to make and use the same.

My invention relates to improvements in mechanism for operating the breech-closure of automatic or semi-automatic guns; and it especially relates to guns of that class in which the breech-closure is controlled by the action of a vibrating lever carried by or moving with the gun during the recoil and counter-recoil.

This invention relates more particularly to an adjustable camming device adapted to engage the breech-operating lever on counter-recoil, but to yield to the said lever during the recoil of the gun.

The invention is especially applicable to guns of the type shown in the patent to William H. Driggs and Vernon C. Tasker, No. 625,326, granted May 23, 1899, and reference may be made to this patent for the various operative parts of the gun therein shown, but which do not form a part of my present invention, and hence are not shown herein.

Reference is had to the accompanying drawings, in which the same parts are indicated by the same letters throughout the several views.

Figure 1 is an elevation of part of the gun and slide of a recoil-mount, such as that shown in the patent aforesaid, the gun being broken away to show the right-hand side of the slide. Fig. 2 represents a section along the broken line 2 2 of Fig. 1 and looking in the direction of the arrows. Fig. 3 represents a section along the line 3 3 of Fig. 2 and looking down. Fig. 4 is a detail view of the fixed member of the cam, and Fig. 5 is a detail view of the yielding member of the cam, which two members together operate the breech mechanism on counter-recoil.

A represents the gun proper, which is provided with dovetail ribs *a*, engaging in the

guideways *b* of the slide *B*, which slide is trunnioned on the gun-mount in the usual well-known way and need not be further described herein. The gun-body or jacket on the same projects downward at *A* and terminates in a bearing *A*² for the operating-shaft *C*, which operates the breech mechanism, which latter not being a part of my invention is not shown. This shaft carries a hand-lever *C*² for operating the mechanism by hand, and also the arm *C*², with lug *c*, for operating automatically or semi-automatically, as will be hereinafter described. The rod *D* is under tension of a spring (indicated at *D*²) and fully described in the patent to Driggs and Tasker aforesaid and tends to keep the hand-lever *C*² to the left, with the breech-block in a closed position, except when operated either by hand or by the automatic attachment hereinafter described.

Between two downwardly-projecting arms *B*², attached to or integral with the slide *B*, the cam-plate *E* is pivoted, as on the bolt *F*. This cam-plate is normally pressed inward toward the axis of the gun by means of the spring *M*. This cam-plate is perforated, as at *E*², (see Fig. 5,) to receive the fixed cam *H*², (see Fig. 4,) which is secured to or integral with the plate *H*, which latter plate is secured to the slide spanning the arms *B*². The cam *H*² has a flat upper surface *h*, a curved engaging surface *h*², and a rounded releasing-surface *h*³. The pivoted cam *E* has a cam-surface *e*, flat face *e*², shoulders *e*², and a locking-face *e*³. On the back of the pivoted cam *E*, I provide arms *e*⁴, between which the bell-crank lever *K* is pivoted, as on the pin *L*. The arm *k* of this bell-crank lever *K* engages the lug *h* on the plate *H* when the bell-crank lever is swung up or to the right, (see Fig. 2,) and thus the cam-plate *E* may be swung about its pivot to clear the lug *c* when the gun is to be operated by hand and not automatically or semi-automatically. When set for automatic or semi-automatic firing, the parts are in the position shown in Figs. 1, 2, and 3. Now suppose the gun to be fired. It will recoil in its slide, causing the lug *c* to engage the cam-face *e* and to press the cam-plate *E* back out of the way against the action of the spring *M*. The lug *c* will at the same time pass over the flat

face h of the fixed cam H' . As soon as the lug c passes in rear of the shoulder e^2 of the movable cam E the latter will swing out again under the influence of the spring M , mean- 5 while the gun continuing its recoil to the rear. At the end of its recoil the gun is forced forward again by the recoil-spring, the lever C' meantime retaining the position shown in Fig. 1 until the lug c strikes the shoulder e^2 of the cam-plate and the shoulder C^2 and shaft C are rotated, the gun continuing its onward movement to its initial or firing position. As the arm C^2 continues to swing backward the lug c would have a tendency to press the cam-plate E outward and free itself before the breech was entirely open; but this lug after traveling a short distance down on the shoulder e^2 passes on to the curved face h^2 of the fixed cam H' , and moving down this face it 10 passes beneath the releasing-face h^3 , allowing the breech mechanism to return to the initial or closed position unless some independent stop be put in to prevent this. Such a stop is generally supplied in the extractor mechanism, as is well known in the art and as is shown, for instance, in the patent to Driggs and Tasker aforesaid; but this not being a part of my present invention need not be discussed herein.

15 30 When the parts are set for automatic or semi-automatic firing, if it be attempted to open the breech by hand, as by swinging the hand-lever to the right, as in Fig. 1, the lug c will strike on the face e^3 of the cam E and it will be impossible to open the breech by hand unless the bell-crank lever K is turned up and the cam-plate E is thus thrown out of engagement. When this is done, the gun may be operated by hand in the ordinary way.

35 40 While for convenience of description I have shown this invention as applied to a gun-mount of the type shown in the patent to Driggs and Tasker aforesaid, I do not mean to confine myself to the details of that particular mount or of any particular mount or of any particular breech-closure, the invention being applicable to almost any of the types of breech-closures in which the breech-block is moved by an oscillating lever and in 45 50 which it is desired to automatically operate that lever on the counter-recoil of the gun.

Having thus described my invention, what I claim, and desire to secure by Letters Patent of the United States, is—

55 1. In a gun, the combination with a vibrating arm and breech mechanism operated thereby, of a stop engaging said arm consisting of a fixed member and a yielding member, the arm first engaging the yielding member of said stop, and then passing on to the fixed member, substantially as described.

2. In a gun, the combination with a vibrating arm and breech mechanism operated thereby, of a stop engaging said arm consisting of a fixed cam and a yielding cam, the arm first engaging the yielding cam of said

stop, and then passing on to the fixed cam, substantially as described.

3. In a gun, the combination with a rock-shaft and breech mechanism operated thereby, of an arm on said shaft and a stop engaging said arm consisting of a fixed member and a yielding member, the arm first engaging the yielding member of said stop, and then passing on to the fixed member, substantially as described.

4. In a gun, the combination with a rock-shaft and breech mechanism operated thereby, of an arm on said shaft and a stop engaging said arm consisting of a fixed member and a yielding member, the arm first engaging the yielding member of said stop, and then passing on to the fixed member, with a spring for restoring the yielding member to the initial position, substantially as described.

5. In a gun, the combination with a rock-shaft operating the breech mechanism and a spring-constrained arm on said rock-shaft normally holding the breech mechanism in the closed position, of a second arm on said rock-shaft, and a stop for said second arm consisting of a fixed member and a yielding member, substantially as described.

6. In a gun, the combination with a rock-shaft for operating the breech mechanism and a spring-constrained arm on said rock-shaft normally holding the breech mechanism in the closed position, of a second arm on said rock-shaft, and a stop for said second arm consisting of a fixed member and a yielding member, and means for throwing said yielding member into and out of engagement with said second arm, substantially as described.

7. In a gun, the combination with a rock-shaft carried by the gun-body and operating the breech mechanism and a spring-constrained arm on said rock-shaft for holding the breech mechanism normally in the closed position, of a second arm on said rock-shaft, and a stop for said second arm secured to the gun-mount and consisting of a fixed member and a yielding member, substantially as described.

8. In a gun, the combination with a rock-shaft carried by the gun-body and operating the breech mechanism, and a spring-constrained arm on said rock-shaft holding the breech mechanism normally in the closed position, of a second arm on said rock-shaft, and a stop for said second arm secured to the gun-mount and consisting of a fixed member and a yielding member, and means for throwing said yielding member into and out of engagement with said second arm, substantially as described.

In testimony whereof I affix my signature in presence of two witnesses.

ALBERT W. ERDMAN.
